Attorney

UNITED STATES PATENT OFFICE.

WILLIAM A. DICKINSON, OF NEWARK, NEW JERSEY, ASSIGNOR TO SEARLS MANUFACTURING COMPANY, OF NEWARK, NEW JERSEY, A CORPORATION OF NEW JERSEY.

ADJUSTABLE HOLDER.

SPECIFICATION forming part of Letters Patent No. 739,482, dated September 22, 1903.

Application filed June 23, 1903. Serial No. 162,806. (No model.)

To all whom it may concern:

Be it known that I, WILLIAM A. DICKINSON, a citizen of the United States, residing at Newark, in the county of Essex, State of New Jersey, have invented certain new and useful Improvements in Adjustable Holders, of which the following is a specification, reference being had therein to the accompanying drawings.

10 This invention relates to an adjustable holder, and particularly to a metallic structure having a resilient body.

The invention has for an object to provide a holder for bottles and glasses and other objects having a series of separate base-supports connected by lateral resilient portions, whereby the body of the holder is rendered automatically adjustable to differences in the size of the articles inserted therein, so as to 20 maintain the proper frictional hold thereon.

A further object of the invention is to provide an improved construction of holder formed from a single piece of material having radiating base portions and lateral resilient body portions integral with and extending between the adjacent base portions.

Other and further objects and advantages of the invention will be hereinafter set forth and the novel features thereof defined by the 30 appended claims.

In the drawings, Figure 1 is a perspective of the holder, a bottle being indicated by dotted lines therein. Fig. 2 is a plan thereof. Fig. 3 is a holder similar to Fig. 1, having an integral handle formed thereon and adapted to support a glass; and Fig. 4 is a perspective of a bottle-holder having a vertically-extending body portion to receive the neck of a bottle, as indicated by dotted lines 40 therein.

Like letters of reference refer to like parts in the several figures of the drawings.

The letter A designates the base-supports for the holder, any desired number of which 45 may be provided and which in the present illustration are shown as radiating from a central point and formed of a piece of material bent upon itself at the free end of the base

A', while at the opposite end A² the body portion B of the holder extends in a substantially vertical plane and is merged into and integral with the base portions upon opposite sides thereof. This body portion is provided at its upper end with a segmental cross-bar B'. The parts of the holder, as shown in Figs. 1 and 2, are adapted to be formed of a single piece of material—for instance, wire—the free ends of which may be joined at any desired point by welding—for example, as shown by dotted lines at B²—60 while the segments of the cup-shaped body thus formed are laterally resilient in order to receive and frictionally engage the object inserted in the holder—for instance, a bottle—as indicated by dotted lines in Fig. 1. 65

The form of the invention shown in Fig. 3 is similar to that shown in Fig. 1, with the exception that the free ends of the wire are carried from the end of one of the bases A to form a handle C. The wire at the end of the 70 base is bent back upon itself, as indicated at C', and then upward again to form the handle C and finally attached to the cross-bar B' of adjacent body portions, as indicated by dotted lines at C². 75

In Fig. 4 the construction is similar to that shown in Fig. 1, with the exception that the body portions B are extended upward at their upper portions D to present a long bearing 80 for the neck of the bottle and there provided with segmental cross-bars D', shown at the free ends of the wire forming this holder, being connected together upon one of these bars, as indicated at D². When this elongated body is provided, it is frequently desirable to provide means to limit the lateral expansion of the sections thereof, which may be accomplished by means of the ring D⁸, located upon the outside of the holder at the bent portion A² between the base-sections 85 and the body portion. 90

It will be seen that the holder shown in Fig. 1 is adapted to receive a round-bottom or other shaped bottle, while that shown in Fig. 3 is particularly adapted and intended 95 for a glass or tumbler and the form in Fig. 4

for receiving the neck of an inverted bottle, which is especially desirable for use in show-window displays. While these applications of the invention have been shown, the improvements are adapted for use with many other articles and present a radially-resilient body, which renders the holder self-adjustable to articles of different sizes, and being light they will readily cling to and be carried by the articles if the same are picked up, and consequently remain in place to support the articles when they are again placed upon a fixed support.

The invention also presents a holder formed from a single piece of wire or other similar material in which the parts are so disposed as to secure a firm base-support with the greatest resiliency and adjustability in the body of the holder. When thus made of a single piece of material, there are but two ends to be joined together by soldering or brazing, and thus a stronger and more efficient holder is produced with the use of a small amount of material.

It will be obvious that changes may be made in the details of construction and configuration without departing from the spirit of the invention as defined by the appended claims.

Having described my invention and set

forth its merits, what I claim, and desire to secure by Letters Patent, is—

1. A holder comprising a series of radiating base portions and independent laterally-resilient body portions extended upward and outward from the inner ends of separated base portions and connected at their upper ends by a horizontally-disposed bar. 35

2. A holder formed from a single piece of material and comprising base portions bent upon themselves one strand of each portion being carried outward and upward from the inner end of the base into a vertical plane and the opposite strands of each base portion connected at the top of the vertical portion 45 by a segmental bar.

3. A holder formed from a single piece of wire and comprising base portions bent upon themselves one strand of each portion being carried upward into a vertical plane and the 50 opposite strands of each base connected by a cross-bar, and an integral handle portion extended from the free end of one base upward and connected to adjacent cross-bars.

In testimony whereof I affix my signature 55 in presence of two witnesses.

WILLIAM A. DICKINSON.
